PAUL OTTO MOTHES, OF NORTH BERGEN, NEW JERSEY, ASSIGNOR OF ONE-HALF TO STEIN-TOBLER COMPANY, INC., A CORPORATION OF NEW YORK.

FABRIC FRAME AND FABRIC-MOUNTING APPARATUS FOR EMBROIDERY MACHINES.

Application filed November 13, 1926. Serial No. 148,187.

This invention relates to improvements in fabric frames and fabric-mounting apparatus for embroidery machines.

One of the objects of this invention is to produce a fabric-frame, preferably adapted for embroidery machines of the Schiffl type, and having a series of adjacent tambour-frames for mounting individual pieces to be embroidered, in which a stationary frame member is formed of a plurality of permanently interconnected hoop-like tambour-frame elements, and the other hoop-like element is movable and is insertable within the stationary element.

Another object of the invention is to provide a fabric-frame having a series of tambour-frames composed of stationary and movable frame elements, in which a single bar will serve as the common side of two adjacent stationary tambour-frame elements.

Still another object of the invention is to provide, in combination with suitable supporting members, a series of vertical and horizontal bars permanently connected to form a stationary frame having rectangular tambour-frame openings or compartments arranged adjacent to each other, one of such bars providing a common outer stationary frame-member for adjacent tambour-compartments and an inner hoop-like tambour-frame element removably mounted in said stationary frame.

Another object of this invention is to provide means for inserting an individual fabric to be embroidered and a removable tambour-frame element in each of said stationary tambour-frame compartments bounded, as aforesaid, by the stationary frame element.

Another object of my invention is to provide novel method and means for initially mounting fabric over a stationary frame-element and then tightening the said fabric in place between the sides and ends thereof by the insertion of a movable inner frame-element.

Another object of the invention is to produce an inserting device in which removable means are employed for initially stretching and positioning in registration with the opening in an outer stationary frame-element, the fabric to be embroidered, and then guiding and inserting an inner frame-element to hold the fabric in tightened condition within said frame opening.

With these and other objects in view, the

invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:

Fig. 1 is a fabric-frame embodying my invention, showing a series of fabric pieces mounted in position to be embroidered at one end and another piece in the process of being inserted within a frame-compartment.

Fig. 2 is a section on the line 2—2 of Fig. 1, showing the insertion element mounted on the fabric-frame and a piece of fabric mounted on said insertion element prior to initial stretching by the insertion element;

Fig. 3 is a similar section showing the insertion member closed to initially span the material and retain it in tightened relationship above the frame-compartment into which it is to be inserted and also showing the inner frame-member arranged above the fabric in said insertion element before being depressed through said insertion element and into contact with the stationary frame-member;

Fig. 4 is a similar section showing the inner ring or removable frame-member partially inserted within the outer stationary frame-member with the inserting device still in place;

Fig. 5 shows a similar view illustrating the position of the fabric when the ring or inner hoop-like frame-member has been partially inserted into the stationary frame and the insertion element has been moved over with its insertion aperture registering with the next frame and with a portion overlying said partially inserted hoop-like inner frame-member so as to permit further depression of the same within the frame;

Fig. 6 illustrates the insertion device and the movable fabric ring depressed into final position with the insertion device also in proper position over the next adjacent frame opening to permit insertion of another piece of fabric;

Fig. 7 is a vertical section on the line 7—7 of Fig. 4, looking in the direction of the arrow, showing the insertion device applied with a ring inserted therethrough and partially inserted into cooperative relationship with the stationary frame-member;

Fig. 8 is an enlarged fragmentary section on the line 8—8 of Fig. 1, looking in the direction of the arrow;

Fig. 9 is a view, in perspective, of the inserting device employed by me;

Fig. 10 is an enlarged fragmentary view in front elevation of a tambour frame composed of the integral outer members and movable inner members;

10 Fig. 11 is a retaining clip employed by me for retaining the gathered edges of the embroidered pieces; and

15 Fig. 12 is a section on the line 12—12 of Fig. 1, showing one of the clips in holding position.

Referring now to these drawings, which illustrate a preferred embodiment of my invention, 1 indicates a fabric frame which is adapted to be supported in vertical position 20 in an embroidery machine of the Schiffli or similar type and which when it is desired to embroider individual pieces, such as gloves, handkerchiefs and the like, is intended to be substituted for the usual Schiffli fabric-frame. These individual-piece frames require a series of individual fabric-stretching means, such as tambour-frames, for the purpose of spanning, stretching and holding the individual pieces in position to be embroidered by the needles, it being understood that when the embroidery machine is provided with duplicate or top and bottom rows of needles, my fabric-frame may be likewise duplicated, in which case, the duplicate top 35 and bottom frames would be suitably connected together and supported by the mechanism of the machine. Such duplicate frames, however, being identical, it will only be necessary to describe one of the same 40 adapted for cooperation with a single row or series of needles.

It will be understood that these frames are usually disposed vertically to cooperate with horizontal reciprocating needles and extend 45 the entire length of the Schiffli machine. They are, therefore, very long and heavy and preferably include therein an individual tambour-frame to cooperate with each needle so as to avoid the removal of needles and to 50 permit a relatively large number of individual pieces to be embroidered simultaneously.

In mounting the fabric it is desirable to have as few loose parts as possible and to 55 make the frame parts as light as possible.

By the use of my invention, I am enabled to produce an embroidery machine frame embodying a series of cooperating tambour or individual fabric-stretching frames in which 60 the outer elements or members of the tambour-frame are stationary and a plurality or series thereof are formed in a single piece, and preferably comprise an integral part of the embroidery machine frame. Said series 65 of outer tambour-frame elements are also so

formed as to cause adjacent frame-compartments to have common side frame-bars.

In the embodiment illustrated, supporting bars 2, 2^a are provided which extend the entire length of the machine and these bars 70 are connected together by a series of spaced stationary parallel vertical bars 3. The spaces thus formed are again subdivided by stationary horizontal bars 4, 4^a to provide at the middle of the machine frame a series of tambour-frame openings 5 bounded by said stationary vertical and horizontal bars, and to provide at the upper end of each tambour-frame compartment a covered holder-compartment 6 for excess material extending 75 over the top end and a lower hanger compartment 7 for the excess material extending below said tambour-frames. The upper holder-compartment is covered on opposite sides by a piece of tightly fitted flexible fabric extending to a point slightly less than the width of the holder-compartment so as to enable passage of the excess material beneath the cover and the holding thereof within the compartment by said cover. The lower compartments need not be covered as the excess material will hang down therein by gravity.

The individual pieces of fabric are inserted within the stationary frame-elements simultaneously with the insertion therein of the removable inner frame-element. In order to mount these individual pieces of fabric in the said frames, an individual piece of fabric 9 is initially stretched over and in proximity to a stationary frame-element by what I shall term "an inserter" 8 and then an inner ring 10 guided by said inserter is inserted within the frame opening.

My insertion device or inserter is preferably composed of a pair of hinged members 11 and 12, comprising a base member 11 provided with an opening 13 of a size similar to and adapted to register with the opening 5 of the outer frame-element, the said base member being provided, at the marginal side, and top and bottom edges of the opening 13 with upwardly-disposed flanges 14, 14', 14^a and 14^b which when the inserter is properly positioned over a frame opening 5 will register 110 with the side and end portions of a frame and said opening 13 and flanges are adapted to permit the inner member to pass therethrough and therebetween, as hereinafter specified. The other hinged member 12 comprises an initial stretching plate also having a registering opening 15, the side and end edges of which are adapted to close over the edges of the said flanges so that when a piece of fabric 9 is mounted over the flanges 14, 14', 14^a and 14^b and opening 13 in the base plate, the closing of the top hinged plate 12 will cause the edges of the opening 15 to engage and initially stretch the fabric 9. The base plate is preferably guided into and held 115

in registration with the openings in which the fabrics are to be inserted by providing the bottom surface of the base plate with guide members, comprising blocks and strips 16, 5 16^a adapted to fit within an adjacent frame opening 5 and to abut against the opposite side and end bars or tambour-frame elements, and in the case of the insertion of a fabric in an outside or marginal frame opening, the 10 guide members abut against end bar portions 4', 4^b provided for that purpose.

When the fabric is thus initially stretched between the base and stretching members to extend over an integral tambour-frame element, the inner frame-element 10 is then positioned over the said fabric between the flanges, 14, 14', 14^a and 14^b in the base plate and is forced downwardly between the said guiding flanges and into resilient frictional 20 contact with the integral tambour-frame bars in the said machine frame. This inner frame-member 10 preferably has its bottom edge rounded off to facilitate entrance and is also preferably bulged outwardly at its middle 25 portion 10^a so as to enable a more thorough frictional and resilient engagement with the integral frame bars and when this inner ring or hook-like frame-element is resiliently engaged by the said integral frame bars or 30 outer frame-element, the insertion device is removed and placed in registry with an adjacent tambour-frame opening.

During the setting of this insertion device in place for insertion of fabric in the next 35 frame, the under side of the flat portion 11^a thereof will engage the ring previously inserted and will form a convenient means for forcing it down between the said integral frame bars until the upper edges thereof are 40 flush with said integral frame element or bars, whereupon the operation hereinabove described will be repeated for the insertion of another individual piece of fabric, and these operations may be continued if desired 45 until all the tambour-frame openings in the entire machine frame are filled with such pieces to be embroidered.

In the preferred embodiment of my invention shown, an aligning pin 11^b for the fabric piece is provided on the base plate 11, and a notch 12^a is cut out of the stretching top plate 12 to permit closing thereof for the purpose of stretching the fabric, as aforesaid.

55 I preferably, as aforesaid, provide above the integral frames shown a series of compartments 6 covered tightly by a flexible fabric 6^a so as to enable any piece-portions projecting upwardly from the tambour-frames 60 to be engaged, covered and held in place. Those portions of the fabric piece projecting downwardly, simply hang, as aforesaid, by gravity. In case, however, the piece to be embroidered extends beyond the edges of the 65 tambour-frame, the overhanging edge por-

tions are preferably gathered or rolled together adjacent to the side of the tambour-frame and are secured in place thereon by means of a clip or clamp 17 so as to be snugly held out of the way of the embroidery needles 70 cooperating with the adjacent frame. These clips 17 may, however, be applied after the insertion of the next adjacent piece of fabric and portions of the fabric in adjacent tambour-frames may be rolled together and held 75 by a single clip.

In the preferred embodiment of my invention, the stretching member 12 is provided with an inwardly-directed marginal flange 12^a at the upper edge thereof which, when this 80 member 12 is closed over the member 11, will engage the individual fabric piece and assist in stretching it over the abutting edge of the said member 11.

Having described my invention, I claim:— 85

1. A fabric-frame for embroidery machines comprising supporting members extending longitudinally of the embroidery machine, a series of outer tambour-frame elements irre- 90 movably and permanently connected to said supporting members, and movable inner tam- 95 bour-frame elements adapted to frictionally engage pieces of material between themselves and said outer elements and means for initially stretching individual pieces of fabric over said outer frame elements and guiding the insertion of said inner element within the outer element.

2. A fabric-frame for embroidery ma- 100 chines comprising top and bottom support- 105 ing members extending longitudinally of the embroidery machine, a series of outer tam- 110 bour-frame elements permanently connected between said supporting members, movable inner tambour-frame elements adapted to frictionally engage pieces of material between themselves and said outer tambour-frame ele- 115 ments, and means for initially stretching in- 120 dividual pieces of fabric over said outer tam- 125 bour-frame elements, and guiding the inser- 130 tion of said inner elements within the outer elements, comprising a base-plate having an opening adapted to register with the openings of the outer tambour-frame elements and to seat the inner frame elements, and means for initially stretching said fabric over the said opening in the base plate.

3. A fabric frame for embroidery machines comprising top and bottom supporting mem- 120 bers extending longitudinally of the em- 125 broidery machine, a series of outer tambour- 130 frame elements permanently connected be- 130 tween said supporting members, movable in- 130 ner tambour-frame elements adapted to fric- 130 tionally engage pieces of material between them- 130 selves and said outer tambour-frame ele- 130 ments, and means for initially stretching in- 130 dividual pieces of fabric over said outer tam- 130 bour-frame elements, and guiding the inser- 130 tion of said inner elements within the outer

elements, comprising a base-plate having an opening adapted to register with the openings of the outer tambour-frame elements and to seat the inner frame elements, marginal flanges at the edges of the opening in the base plate, said flanges registering with the walls of the outer frame-elements and extending outwardly to provide a raised fabric seat and another member having an opening adapted to embrace or hug the edges of said seat to initially stretch and yieldingly hold the fabric surrounding all parts of said base-plate opening and to permit the insertion of the inner tambour-frame element into frictional engagement with the walls of the outer member.

4. A fabric-frame for embroidery machines comprising top and bottom supporting members extending longitudinally of the embroidery machine, a series of outer tambour-frame elements permanently connected between said supporting members, movable inner tambour-frame elements adapted to frictionally engage pieces of material between themselves

and said outer tambour-frame elements, and means for initially stretching individual pieces of fabric over said outer tambour-frame elements, and guiding the insertion of said inner elements within the outer elements, comprising a base-plate having an opening adapted to register with the openings of the outer tambour-frame elements and to seat the inner frame elements, marginal flanges at the edges of the opening in the base plate, said flanges registering with the walls of the outer frame-elements and extending outwardly to provide a raised fabric seat and another hinged member having an opening adapted to embrace or hug the edges of said seat to initially stretch and yieldingly hold the fabric surrounding all parts of said base plate opening and to permit the insertion of the inner tambour-frame elements into frictional engagement with the walls of the outer member.

In witness whereof I have signed my name to the foregoing specification.

PAUL OTTO MOTHES.
